UNITED STATES PATENT OFFICE.

RANSOM W. DAVENPORT, OF DETROIT, MICHIGAN, ASSIGNOR TO DETROIT STOVE WORKS, OF DETROIT, MICHIGAN, A CORPORATION OF MICHIGAN.

ELECTRICAL HOT-PLATE.

1,158,451.

Specification of Letters Patent.

Patented Nov. 2, 1915.

Application filed October 10, 1914. Serial No. 866,075.

To all whom it may concern:

Be it known that I, RANSOM W. DAVENPORT, a citizen of the United States of America, residing at Detroit, in the county 5 of Wayne and State of Michigan, have invented certain new and useful Improvements in Electrical Hot-Plates, of which the following is a specification, reference being had therein to the accompanying 10 drawings.

The invention relates to electric heaters and more particularly to constructions designed for use as hot-plates. It is the object of the invention, first, to obtain a construction 15 in which a substantial support is afforded for the hot-plate with a minimum loss of heat.

It is a further object to obtain a construction which is easily assembled and 20 placeable, and further to provide freedom for expansion and contraction of the unit.

In the drawing, Figure 1 is a plan view; Fig. 2 is a cross section.

A is a plate forming the top of the stove, 25 which is cut away at B for the electric hot-plates C. These hot-plates, which are electrically heated by any suitable construction (not shown), are provided with heat distributing top surfaces of an area to substantially fill the opening or cut away portion B. It is, however, desirable to prevent the loss 30 of heat from the lower face of the heater and also from the marginal edge thereof and through the mechanical supports. To 35 this end I have devised a construction in which the heat losses are minimized as follows. The edge of the plate A adjacent to the aperture B is preferably tapered to a thin or substantial knife edge D, which is 40 separated by an air space from the periphery of the hot-plate C.

E is a heat-reflecting ring surrounding the hot-plate C and the space intermediate the same and the knife edge D.

45 F is a body of thermal insulation arranged beneath the plate C and held in a suitable casing G.

H are supports distributed around the hot-plate, being preferably three in number 50 and being preferably in the form of U-

shaped brackets, the outer ends of which are secured to the bottom of the top plate A, while their inner ends are stepped to form supports for the hot-plate C, the ring E and the casing G containing the thermal insulation F. The brackets H are of a cross section which will secure the requisite strength for mechanical support with a minimum area for the conduction of heat, while the length resulting from the returnbent or U- 55 shaped form will greatly impede heat conduction. Furthermore, the step shoulder I which supports the heater C is limited to an exceedingly small area to avoid heat conduction. The shoulder J which supports 60 the casing G is positioned to hold this casing and the insulation F contained thereby below and out of contact with the hot-plate C, leaving an air space therebetween. The shoulder K, which supports the ring E is 65 also positioned to space said ring from the periphery of the hot-plate C and the knife edge D of the plate A. The dissipation of heat excepting through the upper or work 70 surface of the plate is very slight and at 75 the same time a substantial support is afforded for the plate, and the latter is substantially continuous with the top plate A. The upper surface of the plate C is slightly elevated above the plane of the plate A to 80 hold the heated vessel out of contact with the latter.

The hot-plate C may be made readily removable by providing it with a depending lug L having contacts M for engaging the 85 co-operating contacts in a terminal connection N secured to the bottom of the casing G. This permits of detaching the plate C by merely lifting it off from its support, and upon replacing it upon the support the 90 electrical connections are automatically made.

What I claim as my invention is:—

1. The combination with an electrically heated hot-plate, a deflector ring inclosing 95 the same, and a thermal insulation beneath the same, of a common support for said hot-plate, ring and insulation, each of the same being separately removable from said support. 100

2. The combination with an apertured plate, of an electrical hot-plate located in the aperture and spaced from the edge thereof, and substantially U-shaped supports secured to said apertured plate and having bearings at their opposite ends for loosely supporting said hot-plate and stepped to maintain the hot-plate centered within said aperture. 65
- 5 3. The combination with an apertured plate, of an electrical hot-plate arranged in the aperture of said plate, thermal insulation for the bottom of said hot-plate, and brackets secured to and depending from the 70 apertured plate, supporting the hot plate in a spaced relation to the edge of said aperture and supporting the insulation in a spaced relation to the bottom of the hot-plate. 75
- 10 4. The combination with an apertured plate, of an electrical hot-plate located in the aperture and spaced from the edge thereof, a reflecting ring surrounding said hot-plate and spaced therefrom and from 80 the edge of the apertured plate, thermal insulation below said hot-plate, and a plurality of U-shaped brackets secured to and depending from said apertured plate and having stepped bearings for supporting said 85 hot-plate, reflector ring and thermal insulation. 90
- 15 5. The combination with an electrical hot-plate, of a plate apertured to receive said hot plate and having the edge of the aperture tapered to a thin edge to limit the heat 95 conducting surface, a reflector ring interposed between the hot-plate and said tapered edge, and means for indirectly supporting said hot-plate from said apertured plate. 100
- 20 6. The combination with an apertured plate having the margin surrounding the aperture tapered to a thin edge, of an electrical hot-plate located in said aperture, a reflector ring surrounding the periphery of 105 said hot-plate spaced therefrom and from said thin edge, thermal insulation below said hot plate, and a bracket secured to said apertured plate extending indirectly to said hot-plate and supporting the same together 110 with said ring and thermal insulation. 115
- 25 7. The combination with an apertured plate, of a hot-plate located in said aperture, thermal insulation below said plate, said hot-plate and insulator being relatively movable, electrical connection for said hot-plate having contacts fixedly located in said thermal insulation, and coöperating contacts on said hot-plate for detachably engaging said first-mentioned contacts. 120
- 30 8. The combination with an apertured plate, of a plurality of U-shaped brackets secured thereto and having stepped bearings at their inner ends, an electrical hot-plate located in said aperture supported on one 125 of the steps of said bearing, a casing below 65 said hot-plate supported on another of said bearings, thermal insulation in said casing, a heat-reflecting ring surrounding said hot-plate spaced from the same and the edge of the aperture and supported upon another 70 step of the bearing, electrical contacts carried by said casing, and coöperating contacts on said hot-plate detachably engaging said first-mentioned contacts. 75
- 35 9. The combination with an electrically heated hot plate, of a reflector ring inclosing said plate and spaced therefrom, and a plurality of common supports for said plate and ring maintaining their spaced relation. 80
- 40 10. The combination with an electrically-heated hot-plate, of a reflector ring inclosing the same, and a thermal insulation spaced beneath the hot-plate, and means forming a common support for the hot-plate, reflector ring and insulation. 85
- 45 11. The combination with an electrically heated hot-plate, of a reflector ring inclosing the same and spaced therefrom, a thermal insulation spaced beneath the hot-plate, and a plurality of common supports for the 90 hot-plate, reflector ring and insulation maintaining the same in their proper spaced relation. 95
- 50 12. The combination with an electrically-heated hot-plate, of thermal insulation spaced below the hot-plate, and a plurality of common supports for the insulation and hot-plate, maintaining the spaced relation between the same. 100
- 55 13. The combination with an electrically-heated hot-plate, of a reflector ring inclosing the same, and spaced therefrom, a thermal insulation spaced from the hot-plate beneath the same, and a plurality of members similarly stepped to support said hot-plate, reflector ring and insulation and maintain 105 the desired spaced relation between the same. 110
- 60 14. The combination with supporting means, of an electrically-heated hot-plate carried by said means, and free to be lifted therefrom, and coöperating electrical contacts guided into or out of engagement with each other when the plate is being removed or replaced, by the engagement of said plate with said supporting means. 115
- 65 15. The combination with an electrically-heated hot-plate, of a thermal insulation beneath the same, a common support for the hot-plate and insulation, the hot-plate being removable from said support independently 120 of the insulation, contact members carried by the hot-plate projecting into an opening in the insulation and contact members with which those carried by the hot-plate are engaged or disengaged according as said plate 125 is displaced to or from its normal position. 125
- 70 16. The combination with an electrically-heated hot-plate, and an incased thermal in-

sulation beneath said hot-plate, of coöperating contact members respectively carried by the hot-plate and insulation, and a common support for the hot-plate and insulation, the hot-plate being removable from said support independently of said insulation, the coöperating members being guided out of or into engagement with each other when

said plate is being removed or replaced by engagement of said plate with the support. 10

In testimony whereof I affix my signature in presence of two witnesses.

RANSOM W. DAVENPORT.
